Primary Examiner — Sharon S Oum(57) **CLAIM**

The ornamental design for a ventilating fan assembly with solar panels, as shown and described.

DESCRIPTION**1.1** is a left side view of a ventilating fan assembly with solar panels in a closed configuration;**1.2** is a perspective view thereof, but in an open configuration;**1.3** is a front view of **1.1**;**1.4** is a front view of **1.2**;**1.5** is another perspective view of **1.2**;**1.6** is a bottom view of **1.1**;**1.7** is a top view of **1.1**;**1.8** is a right side view of **1.1**;**1.9** is a perspective view of **1.1**;**1.10** is a back view of **1.1**; and**1.11** is a top view of **1.2**.The design is illustrated in the closed configuration, in which the solar panels are folded together; the design is also illustrated in an open configuration, in which the solar panels are unfolded; the parts shown by means of broken lines in the reproductions are not part of the claimed design; in Fig. **1.10**, the horizontal and vertical lines within the central circular area of the fan housing are not part of the claimed design.**1 Claim, 11 Drawing Sheets**(56)
